CLAIM

The ornamental design for the mobile telephone case, as shown and described.

DESCRIPTION

FIG. 1 is a perspective, front-elevational view of a mobile telephone case, with a winder in a closed storage position, showing my new design;

FIG. 2 is a side-elevational view thereof in the winder position of FIG. 1;

FIG. 3 is a rear-elevational view thereof;

FIG. 4 is a top-plan view thereof;

FIG. 5 is a bottom-plan view thereof;

FIG. 6 is a front-elevational view of the mobile telephone case showing my new design, with the winder in an open position;

FIG. 7 is a rear-elevational view thereof in the winder position of FIG. 6;

FIG. 8 is a top-plan view thereof;

FIG. 9 is a bottom-plan view thereof;

FIG. 10 is a front perspective view of the mobile telephone case showing my new design, in the winder position of FIG. 1;

FIG. 11 is a front perspective view of the mobile telephone case in the winder position of FIG. 1, with an inwardly-facing mobile telephone disposed therein, the mobile telephone is shown in broken lines and it does not form a part of the claimed invention;

FIG. 12 is a front perspective view of the mobile telephone case in the winder position of FIG. 1, with an outwardly-facing mobile telephone disposed therein shown in broken lines;

FIG. 13 is a rear perspective view of the mobile telephone case in the winder position of FIG. 7, with an inwardly-facing mobile telephone disposed therein shown in broken lines; and,

FIG. 14 is an exploded, rear perspective view of the mobile telephone case according to the invention.
